UNITED STATES PATENT OFFICE.

FRANK J. COOPER, OF SAN FRANCISCO, CALIFORNIA.

DESIGN FOR A FOLDER.

59,338.

Specification for Design. Patented Oct. 11, 1921.

Application filed October 18, 1920. Serial No. 417,855. Term of patent 7 years.

To all whom it may concern:

Be it known that I, FRANK J. COOPER, a citizen of the United States, residing at the city and county of San Francisco, State of California, have invented a new, original, and ornamental Design for Folders, of which the following is a specification, reference being had to the accompanying drawings, forming part thereof.

The folder is suitable for retaining cards,

papers, books or other miscellaneous articles.

Figure 1 is a view of the folder opened, showing my new design.

Fig. 2 is a view in perspective, showing the folder partially closed.

I claim:

The ornamental design for a folder as shown.

FRANK J. COOPER.
